(57) **CLAIM**

The ornamental design for a broom head, as shown and described.

DESCRIPTION

FIG. 1 is a perspective view of one side of a broom head showing our new design;

FIG. 2 is a perspective view of the other side thereof;

FIG. 3 is a top plan view thereof;

FIG. 4 is a bottom plan view thereof;

FIG. 5 is a side elevation view thereof, the opposite side elevation view being a mirror image; and,

FIG. 6 is an end elevation view thereof, the opposite end elevation view being a mirror image.

The broken lines in the figures depict portions of the broom head that form no part of the claimed design.
